(57) **CLAIM**

The ornamental design for an LED replacement module, as shown and described.

DESCRIPTION

FIG. 1 is a perspective view of an embodiment of an LED replacement module;

FIG. 2 is a side view thereof;

FIG. 3 is a top view thereof; and,

FIG. 4 is a bottom view thereof.

The broken lines shown in the drawings illustrate unclaimed portions of the LED replacement module and form no part of the claimed design.
